UNITED STATES PATENT OFFICE

GASTON DE DUDZEELE, OF PARIS, FRANCE

DEVICE FOR TREATING ROUGH TUBES AND ANALOGOUS ARTICLES WITH LEAD

Application filed November 13, 1928, Serial No. 319,176, and in France November 16, 1927.

My invention relates to a device for lead treating rough hewn tubes employed in the manufacture of tubes.

Lead treating tubes takes place by depositing them, after a suitable chemical treatment, such as by the process forming the subject of my United States Patent Number 1,548,514, for example, on the surface of a liquid lead bath, previously covered over with a flux 10 having a salts of zinc base.

After the rough tube, placed in the center of the flux, has been sufficiently heated, it is plunged in the heart of the mass of lead, taking care at the start to cause the end to descend in the said mass, in such a way that the air or excess flux, existing on the interior of the rough tube, can become disengaged by the open extremity and not remain confined on the interior. When the rough 20 tube is entirely covered with lead, it is taken out at a point of the melting pot where the surface of the lead is free, in order that it does not become polluted with flux. The rough tube therefore floats on the surface of the 25 bath from whence it is easily extracted.

The device forming the object of my invention has for a purpose to establish mechanically, all the operations necessary for assuring a regular and economical lead treating of 30 rough tubes.

The accompanying drawing illustrates, by way of example, one embodiment of my invention.

In the drawing—

35 Fig. 1 is a partial sectional view through the device in the longitudinal sense; and

Fig. 2 is a transverse section along the line 2—2 of Fig. 1.

Referring to the drawing more in detail, 1 40 represents the melting pot, in transverse and longitudinal section. Said melting pot is disposed in an oven containing the hearth destined to assure melting of the lead.

At 2 is shown the separator or diaphragm, 45 destined to divide the surface of the lead bath into two unequal parts, the larger of which contains the flux and in the smaller of which the metallic bath presents a free surface.

50 In Fig. 2 the flux is assumed to be disposed

at A and at B the surface of the lead is assumed to be free. The separator or diaphragm can be of a single piece or in two parts, as shown in Fig. 2. The lower part thereof makes a certain angle with the horizontal corresponding to that which it is necessary to give the rough tube in the heart of the lead bath in order to assure total liberation of the air or flux which passes on the interior of the tube. 55

Several rough tubes can be disposed on the flux side for heating simultaneously and extracted one after another on the free surface side. 60

At 3 is represented a frame forming a bridge, which may be made integral or separate with the heating furnace. Said frame is constituted by any suitable construction such as of channel members, tubes and the like. In Figs. 1 and 2, it is illustrated as composed 65 of channel members.

On said frame is placed at 4, a longitudinal arbor resting on suitable bearings and on which are keyed grooved pulleys, whose number will vary in proportion to the length of 70 the apparatus.

Said pulleys are illustrated at 5. The diameters thereof are unequal and designed in such a way that their exterior surface is tangent to the same cone whose apex lies 75 along the arbor 4 or a prolongation thereof. The angle at the apex of the cone is equal to the angle which the lower part of the separator 2 forms with the horizontal. Said angle is a function of the maximum length of 80 the tubes to be treated. It permits the rough tubes to be given an inclination such that all the flux can escape by reason of its different density as compared to the lead. 85

At 6 are disposed small grooved pulleys 90 whose number corresponds to that of pulleys 5 and whose transverse vertical plane lies in that of the said pulleys 5. Said pulleys 6 act as idlers for an endless chain 7 passing around the pulleys 5 and 6. 95

Proper tension is given to said chain by means of tension rollers 8, mounted within a bracket 9, provided at its extremities with a threaded rod 10, allowing for transverse displacement susceptible to increasing or de- 100

said first named pulleys of decreasing diameters carried by said frame, a chain passing over each pair of said first and second named pulleys, and a finger mounted on each of said chains whereby the articles to be treated are passed around said diaphragm in inclined position from one of said chambers to the other for the purpose disclosed.

4. In a device for treating rough hewn tubes and analogous articles with lead comprising, in combination, an inclined melting pot, a diaphragm disposed in said melting pot in spaced relation to the bottom and parallel thereto, a plurality of channel members disposed on said diaphragm, a pulley mounted in each of said channel members at equal distances from the bottom of said melting pot, a frame disposed above said melting pot, a shaft disposed in said frame, a pulley of large diameter mounted on said shaft opposite the first of said first named pulleys adjacent the lower end of said melting pot, a pulley for each of the remaining pulleys of said first named pulleys of decreasing diameters carried by said shaft, a chain passing over each pair of said first and second named pulleys, and a finger mounted on each of said chains whereby the articles to be treated are passed around said diaphragm in inclined position from one of said chambers to the other for the purpose disclosed.

In testimony whereof I hereunto affix my signature.

GASTON DE DUDZEELE.
